ATTORNEY.

UNITED STATES PATENT OFFICE.

GEORGE A. HOLMES, OF NEWTON CENTER, MASSACHUSETTS, ASSIGNOR TO FRED JOY,
OF WINCHESTER, MASSACHUSETTS.

TURNBUTTON-FASTENER.

1,375,756.

Specification of Letters Patent. Patented Apr. 26, 1921.

Application filed February 26, 1921. Serial No. 448,159.

To all whom it may concern:

Be it known that I, GEORGE A. HOLMES, a citizen of the United States, and a resident of Newton Center, in the county of Middlesex and State of Massachusetts, have invented an Improvement in Turnbutton-Fasteners, of which the following description, in connection with the accompanying drawing, is a specification, like reference characters on the drawing representing like parts.

This invention relates to a fastener or turn-button of the kind commonly used for fastening the curtains of vehicles, and the invention consists in certain novel features of construction which will be hereinafter described, which conduce to low cost of construction and to strength and durability of the fasteners.

The fastener is of the kind in which the curtain or part to be fastened is provided with an oval hole having its margin reinforced by a gromet, which constitutes the movable member of the fastener, while the standing member consists of a base portion having a shank of corresponding oval shape, and a correspondingly oval button or head pivotally connected with the said base and adapted to be passed through the gromet and then to be turned to position to confine the gromet on the said shank, until the button is again turned to position to permit the gromet to pass off over it.

Figure 1 is a front view of a fastener embodying the invention, showing the members engaged;

Fig. 2 a sectional view, on line x^2 of Fig. 1, of the standing member;

Figs. 3 and 4 side and end elevations of the shell which constitutes the outer part of the head or button proper, before assemblage;

Figs. 5 and 6 corresponding views of the oval or filling piece;

Fig. 7 a sectional elevation, and

Fig. 8 an elevation at right angle thereto of the pintle or pivot shank of the button head, also before assemblage; and

Fig. 9 a view of the underside of the assembled and completed button head, ready for assemblage with the base as shown in Fig. 2.

The curtain or part to be fastened, a portion of which is shown at 2 in Fig. 1, has an elongated opening the margin of which is reinforced by an oval gromet 3 which may

be such as usually employed in fasteners of the kind above referred to.

The standing member comprises a base portion having a foot 4 adapted to be secured to the body of the vehicle, or part to which the curtain is to be fastened, and a shank 5 corresponding in shape to the opening in the gromet as shown in Fig. 1, the said base portion preferably being made of sheet metal drawn to the desired shape.

The button proper, or head, is composed in part of a shell 6 consisting of a hollow piece of sheet metal drawn to the proper shape as shown in Figs. 3 and 4, and a pintle piece, which is in the form of a tubular rivet 70 the base flange of which is of oval shape and fits within the open end of said shell, and is secured therein by having the edge portions 8 of said shell turned over upon said base as shown at 80 in Fig. 9.

In order to reinforce the button head and to support the base flange of the pintle while the edges of the shell are being bent into engagement with it, a filling piece 9 is placed in the shell before the pintle piece is introduced, said filling piece being shown as of hollow construction, shaped to fit the inside of the button head shell 6, but being closed at the bottom so as to afford a firm support or anvil for the base flange of the pintle 85 while the edges of the shell are being upset into engagement therewith, and in the subsequent operation of mounting the button on the base portion of the standing member of the fastener.

By making the marginal part of the shell 6 with the projections 8 of the curved shape as shown, the base flange of the pintle piece 7 is firmly engaged when said projections are upset or bent down over it, as shown at 95 80 in Fig. 9, and is substantially covered except for the spaces 17, 18, which serve a purpose which will be hereinafter referred to.

The button proper is assembled and completed by inserting the filler 9 in the shell 6 and then placing the base of the pintle piece 7 against the base of the filler 9 and then turning the marginal portions 8 of the shell 6 over upon the base of the pintle piece 105 by the action of suitable dies.

The button proper composed of the parts shown in Figs. 3 to 8 united as shown in Fig. 9, as has just been described, is pivotally connected with the base piece 4, 5, by 110

the shank of the part 7, which is passed through a perforation at 12 in the end of the shank portion 5 of the base piece, and after having a spring 14 placed thereon, has its 5 end upset or headed as shown at 15 in Fig. 2, so that said spring is interposed between the head 15 of the pintle and the inner surface of the end of the shank 5, and thus causes the base of the button proper to be 10 pressed firmly but yieldingly against the said shank end.

In order to provide for the retention of the button in the position in coincidence with the base shank 5 in position to permit the 15 gromet 3 to be passed over it for fastening or unfastening, or in the position at right angles thereto to confine or fasten the gromet as shown in Fig. 1, the end of the base shank 5 is provided with a raised rib 16 extending 20 the entire length of the major axis thereof, except where interrupted by the pintle hole 12, which rib coöperates with the recesses 17, 18, in the lower face of the button proper, which lie in the major and minor axes 25 thereof.

The rib 16 by engagement with the recess 17 normally holds the button in line with the base shank 5, but when forcibly turned the spring 14 yields permitting the button 30 to rise and be turned so as to confine the gromet, and at the end of a quarter turn the recess 18 engages with the rib 16, and retains the button in holding position until forcibly turned therefrom.

35 The operation is the same as is usual with this type of fastener. When the button is in coincidence with the shank 5 of the base piece the grometed button hole of the curtain is passed over it on to the shank 5 as 40 shown in Fig. 1 and the button is then turned to the position shown in Fig. 1, being raised by the action of the rib 16 from its seat on the shank 5 while turning, and dropping back thereto when the notches 18 come into

engagement with said rib, which insures the 45 retention of the button in the holding position until it is desired to unfasten the curtain again, which may be done by turning the button back into line with the shank 5 of the base, and with the rib 16, in engagement 50 with the notch 17.

The sheet metal button constructed as herein described is less expensive than when made from solid metal, and furthermore is not liable to become detached from the base 55 piece as sometimes happens when the pintle is connected with the button by a screw thread engagement or something of that nature, whether the button head is solid or hollow.

60 I claim:

1. In a fastener of the character set forth, a standing member composed of a base having a shank oval in sectional shape; combined with a button composed of a hollow 65 shell of corresponding oval shape, and a pintle piece having a base flange of corresponding oval shape secured in said shell by engagement by the marginal part thereof, and a filler in said shell serving as a support for said pintle piece; and a spring interposed between the inner surface of the base shank and an enlargement on the pintle substantially as described.

2. The standing member of a turn button 75 fastener having an oval shank provided on its end with a raised rib along its major axis; combined with a button composed of a hollow shell, a filler contained therein, and a pintle having a base flange secured between said filler and marginal projections of said shell, which projections also coöperate with the rib of the base shank to retain the button in fastening or unfastening position; and a spring which yieldingly holds said 85 button against said base shank.

GEORGE A. HOLMES
